(57) **CLAIM**

The ornamental design for coffee maker, as shown and described.

DESCRIPTION

FIG. 1 is a perspective view of a coffee maker, showing our new design in a first embodiment;

FIG. 2 is a front view of the embodiment shown in FIG. 1; FIG. 3 is a rear view of the embodiment shown in FIG. 1; FIG. 4 is side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1;

FIG. 8 is another perspective view of the embodiment shown in FIG. 1;

FIG. 9 is yet another perspective view of the embodiment shown in FIG. 1; and

FIG. 10 is still another perspective view of the embodiment shown in FIG. 1.

The broken lines in the figures are for environmental purposes only and form no part of the claimed design.

The oblique line shading shows a transparent or translucent surface.

1 Claim, 10 Drawing Sheets
